(57) **CLAIM**

The ornamental design for a fish hook extractor, as shown and described.

DESCRIPTION

FIG. 1 is a front view of a fish hook extractor showing my new design, a rear view being a mirror image thereof;
FIG. 2 is a left side view of the fish hook extractor;
FIG. 3 is a right side view of the fish hook extractor;
FIG. 4 is a top view of the fish hook extractor;
FIG. 5 is a bottom view of the fish hook extractor; and,
FIG. 6 is a top, rear and side perspective view of the fish hook extractor.
